INTERCHANGEABLE TOOTHBRUSH

Benjamin Friedman, New York, N. Y.

Application October 3, 1941, Serial No. 413,391

2 Claims. (Cl. 15—176)

This invention relates to new and useful improvements in an interchangeable tooth brush.

More particularly, the invention relates to a tooth brush having a handle with a recessed head portion to receive a tooth brush refill, or a massaging member refill, or a combination refill. The dominant feature of the invention resides in the manner in which the refills are releasably mounted in position.

In one form of the invention a novel arrangement is proposed whereby a stem is removably mounted through the handle and engages one end of the refill for releasably holding the same in conjunction with stud and socket elements which are mounted on the handle and refill for holding the other end of the refill.

Still further the invention proposes a modified construction in which the refill may be supported in various angular positions to suit individual preferences of various users.

For further comprehension of this invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an interchangeable tooth brush constructed in accordance with this invention.

Fig. 2 is a longitudinal sectional view of the tooth brush shown in Fig. 1.

Fig. 3 is a perspective view of the refill shown in Fig. 1.

Fig. 4 is a perspective view of the refill shown in Fig. 3, but turned around.

Fig. 5 is a fragmentary enlarged detailed view of the stem shown in Fig. 2.

Fig. 6 is a fragmentary sectional view similar to Fig. 2 but illustrating a modified construction.

Fig. 7 is an elevational view of a refill adapted to be used in the interchangeable tooth brush.

Fig. 8 is another fragmentary sectional view similar to Fig. 6 but illustrating still another form of the invention.

Fig. 9 is another sectional view similar to Fig. 6 but illustrating another modification.

The interchangeable tooth brush, in accordance with this invention, includes a handle 10 having a head portion 10^a which is formed with a recess 11 to receive a tooth brush refill 12 which is illustrated mounted in said recess. A stem 13 is removably mounted through the han-

dle 10 and engages one end of the refill 12 for releasably holding the same. A stud element 14 is mounted on the head portion 10^a of the handle and engages a socket element 15, such as a niche, on the other end of the refill 12.

The refill 12 comprises a base section 16 supporting a plurality of bristles or massaging elements 17. The stem 13 is engaged through a tube 18 which is fixedly mounted through the handle 10. The outer end of the stem 13 is provided with a screw 19 having a head portion 20 by which the screw may be turned. The screw 19 threadedly engages a portion of the tube 18. The inner end of the stem 13, indicated by reference numeral 13^a, normally engages an aperture 21 formed in the end of the refill 12.

Figs. 1 and 2 illustrate the tooth brush ready for use. When it is desired to remove the refill 12 it is merely necessary that the head 20 be turned to screw out the stem 13 a little way so that the end 13^a disengages from the opening 21. The refill 12 is now free and may be lifted out. A similar refill may be substituted, or a refill in the nature of a massaging refill illustrated in Fig. 7, and indicated by reference numeral 12'. This refill 12' has the usual base portion 16 formed with the openings 15 and 21 in the end portions thereof. Massaging elements 17' project from its top face.

In Fig. 6 a modified form of the invention is disclosed which distinguishes from the first form in the fact that the stem 13 passes through the handle 10 instead of passing through a tube mounted in the handle as previously explained. The screw 19 of the stem 13 threadedly engages the rear portion of the handle 10. In other respects this form of the invention is similar to the previous form and like parts are indicated by the same reference numerals.

In Fig. 8 still another form of the invention is illustrated in which the refill 12^a is provided with a series of apertures 21^a along one end thereof. The stem 13 is adapted to engage one of these apertures to hold this end of the refill projected a selected amount. The other end of the refill 12^a is pivotally supported by a stud 14^a which engages a conical socket 15^a formed in the end of the refill 12^a. The stud 14^a is shown to be integral with the head portion 10^a of the tooth brush. In other respects this form of the invention is similar to the previous forms.

The stem 13 may be turned to screw out slightly so that the end 13^a disengages from the aperture 55 21^a of the refill 12^a and then the refill may be

pivoted to a new selected position and held in this position by re-engaging the stem 13 with the aperture 21^a now aligned with it.

It is possible to adjust the angular inclination of the refill 12^a to suit the requirements of the user as governed by the manner in which the handle of the tooth-brush is gripped. Also, if the bristles 17 on the end of the refill 12^a having the apertures 21^a wear away, it is possible to extend these bristles to cause the front ends of all of the bristles to assume a position parallel with the back of the brush.

In Fig. 9 still another form of the invention is disclosed which distinguishes from the prior form in the construction of the refill 12^b. This refill is shown provided with a projecting stud 15^b which engages a conical socket 14^b formed in the adjacent portion of the head 10^a of the handle. The stem 13 engages an opening 21 in the other end of the refill for releasably holding it in position.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new, and desire to secure by United States Letters Patent is:

1. An interchangeable tooth brush, comprising a handle having a recessed head portion to receive a tooth brush or massaging member refill, a refill member in said recessed head portion, a stem removably mounted through said handle and engaging one end of said refill for releasably holding same, and stud and socket elements mounted on said handle and refill for holding the other end of said refill said refill having a series of openings engageable by said stem by which the refill may be supported in various positions.
- 5 2. An interchangeable tooth brush, comprising a handle having a recessed head portion to receive a tooth brush or massaging member refill, a refill member in said recessed head portion, a stem removably mounted through said handle and engaging one end of said refill for releasably holding same, and stud and socket elements mounted on said handle and refill for holding the other end of said refill said refill having a series of openings engageable by said stem by which the refill may be supported in various positions, and said stud and socket elements being adapted to pivotally support one end of said refill while said stem supports said other end in various elevated positions.

BENJAMIN FRIEDMAN.
